J. J. GOUGH

ELECTRIC CIGAR LIGHTER

Filed Nov. 26, 1926.

UNITED STATES PATENT OFFICE.

JAMES J. GOUGH, OF CHICAGO, ILLINOIS, ASSIGNOR TO CHICAGO ELECTRIC MANUFACTURING CO., OF CHICAGO, ILLINOIS, A CORPORATION OF ILLINOIS.

ELECTRIC CIGAR LIGHTER.

Application filed November 26, 1926. Serial No. 150,842.

My invention relates to current-consuming appliances of the general class in which the current is used intermittently, such as electric cigar lighters.

Generally speaking, my invention aims to provide an appliance construction for such purposes in which the inner parts can be assembled as a unit before they are inserted in the casing of the appliance, in which the casing can be assembled from parts of various configuration, and in which the attaching of the assembled insert portions to the casing serves to hold the casing parts assembled and also holds the insert portions in their operative dispositions.

More particularly, my invention provides a construction in which the holder for a detachable current-consuming device (as for example for the heater tip for an electric cigar lighter) is securely connected to the circuit wires, the movable switching member and an anchoring member before the resulting assembly is inserted in the casing of the appliance, in which the casing includes a plurality of interfitting parts provided with interengaging shoulder formations, and in which the attaching of one of these casing parts to the said anchoring member secures all parts of the appliance in properly assembled disposition.

Still further and also more detailed objects will appear from the following specification and from the accompanying drawing, in which

Fig. 1 is a central, vertical and longitudinal section through an electric cigar lighter embodying my invention.

Fig. 2 is a reduced elevation of the inserted parts (excepting the push-button), showing these parts as they are initially assembled.

Fig. 3 is an enlarged central and vertical section of the detachable heater tip shown as part of the embodiment of Fig. 1.

Fig. 4 is a plan view of the heater tip, drawn on the same scale as Fig. 3.

In its immediate commercial applications, my invention is particularly suited for electric cigar lighters of a portable type suitable for use on a table or desk. Hence I am illustrating and describing such an em-

bodiment, although my invention might obviously be employed for other purposes by substituting some other current-consuming device for the detachable heater tip of this particular embodiment, or might be supported with its axis horizontal.

In the type here illustrated, the housing of my appliance consists of three relatively interfitting tubular parts which together constitute a tubular standard, together with a base plate drawn upwardly against the lowest of these tubular parts, namely the hollow and downwardly flaring base portion 1. This base portion has its upper end contracted to form a cylindrical tube 1^A and to afford an upwardly directed annular shoulder 6 at the juncture of this tube with the main and downwardly flaring part of the said base portion.

The intermediate tubular part 2 has its lower end telescoped over the tube 1^A and abutting against the said shoulder, while the upper end of the part 2 telescopes over a lower tubular portion 3^A of the uppermost tubular part (or head) 3 and abuts upwardly against a larger diametered annular portion of this head part 3. The shoulder formed by the juncture of the tubular part 3^A with the bottom of the larger diametered main portion of the hollow head 3 also affords an upwardly directed annular seat 4 for engaging an annular insulator 5 which serves to space the metal shell 6 of a socket or holder from the housing of my appliance.

The socket shell 6 comprises a tube equipped at its upper end with the usual bayonet slots 7 for interlocking with anchoring pins 8 on a heater tip, and this tube has a peripheral bead 9 below the said slots and engaging the top of the insulator 5 when my appliance is assembled. Fastened to the socket shell 6 and extending downwardly from it as a rigid metallic extension of this shell is a metal bracket 10 which is secured at its lower end to an insulating bar 11. A resilient metal contact member 12 is fastened at one end to the insulating bar 1 and has its other end normally spaced from the bracket 10 but adopted to be pressed against this bracket by a push button 13 which extends through a lateral per-

foration 38 in the intermediate tubular part of the casing.

One circuit wire 14 is connected to the stationary arm of the resilient contact member 12, which is the movable switching member of my appliance, so that the metal socket shell will be electrically connected to the wire 14 when the push button is pressed inwardly of the casing, thereby also connecting this wire electrically through a metal collar 15 of the heater tip to one end of the high resistance wire 16 of this heater tip.

The companion circuit wire 17 is connected to the terminal 18 of the socket which contacts with the axial terminal 19 of the heater tip, to which axial terminal the other end of the resistance wire 16 is connected. This socket terminal 18 is here shown as extending through and clinched to an insulating disk 20 which slidably fits the socket shell. A companion insulating disk 32, also slidably fits the socket shell 6 and normally seats at one side of the upper end of the bracket 10 and at the opposite side on an inwardly directed finger 21 formed upon the socket shell. A compression spring 36 interposed between the insulating disks 20 and 32 continuously urges the upper disk 20 upwardly, so as to press the wire terminal 18 against the axial terminal 19 of the heater tip.

Both of the circuit wires 14 and 17 extend through a lateral aperture in the tubular casing of my appliance, which aperture is desirably bushed by an insulating ferrule 24 and is here shown as formed in the downwardly flaring base portion 1. The two circuit wires preferably are looped into a knot 23 inward of a ferrule 24, which knot engages the bore of the said ferrule, so as to prevent an outward pull on the circuit wires from straining the connections of the wires to the switching member and the axial socket terminal.

The lower end of the tubular base portion 1 is formed into an outwardly directed radial flange 25 engaging the edge portion of a bottom plate 26 which desirably has an upwardly directed annular boss 37 formed on it radially inward of the said flange to center the bottom plate with respect to the said base portion. Extending upwardly through this bottom plate is a screw 27 which is threaded through the foot 28 of an anchoring bar 29 secured to the insulating bar 11. The length of this anchoring bar 29 is such that the screw 27 when drawing the foot 28 toward the bottom plate 26 will draw the bead 9 on the socket shell downwardly, so as to clamp the insulator 5 against the annular shoulder on the intermediate tubular part 2 of the casing. In doing this, the single screw 27 not only secures the socket and switch assembly within the casing, but also holds the interfitting parts 1,

2, 3 and 26 in firmly assembled relation. When the parts are thus assembled, the metal bracket 10, the insulator 11 and the anchoring bar 29 constitute a rigid anchoring structure which not only secures the interfitting parts in their assembled relation, but also holds the socket securely within the casing, and which anchoring structure carries the switching member.

In manufacturing this appliance, the socket and switch parts (with the exception of the pushbutton 13) are first assembled and connected to the two circuit wires as shown in Fig. 2. Then the pushbutton 13 has its outer and smaller diameter part slipped through the aperture 38 from inside the base portion 1, and the outer ends of the wires are drawn through the top of the relatively superposed three casing portions, after which the bottom plate 26 and the screw 27 are attached as above described.

As a desirable heater tip construction, I am here showing this as including an insulating body 28 (of lava or the like) which has an axial bore 39 and a radially enlarged head 30 provided on its upper face with a spiral groove 31. The lower part of the said insulating body includes a second enlargement 32 upon which the conducting collar 15 is clinched, and this collar is formed to provide the anchoring pins 8 which interlock the heater tip with the bayonet slots 7 of the socket. The high resistance wire 16 has its major portion formed into a spiral coil disposed in the groove 31. One end of this wire extends through the axial bore 29 and is secured to the axial terminal 19, while the other wire end extends through alined bores in the enlarged head 30 and the lower enlargement 32 of the tip body and is clinched to the insulating body by the conducting collar 15. A mica disk 33 provided with a plurality of perforations rests on the top of the spiral coil portion of the high resistance wire and is held in position by an upper collar 34 spun over the head 30.

To prevent the edge of the metal bottom plate 26 from scratching any surface on which my appliance is seated I desirably cement a felt disk 35 to the lower face of this bottom plate and I preferably extend the anchoring screw 27 through an upwardly formed central boss 26^a on the bottom plate, so as to dispose the head of the screw above the surface on which my appliance is seated. By making the anchoring bar of such a length that its foot 28 will be above the boss 26^a of the bottom plate when the parts are assembled, I secure the desired rigid assembly without requiring high accuracy in the proportioning of the various parts which are disposed between the bead 9 of the socket shell and the base plate.

However, while I have illustrated and de-

scribed the appliance of my invention in a type adapted for use on a horizontal surface and including numerous desirable features, I do not wish to be limited to the details of construction and arrangement above described, as many changes might be made without departing either from the spirit of my invention or from the appended claims.

I claim as my invention:

1. In an electric appliance of the class described, an upright tubular casing; a socket insertible in the casing from the upper end of the latter; means interposed between the socket and the casing for relatively insulating these parts and for limiting the downward movement of the socket in the casing; an insulator supported by the holder and extending below the latter within the casing; a switching member mounted on the insulator and movable into and out of contact with a conducting portion of the socket, the switching member having an actuating portion projecting laterally through the casing; and anchoring means interposed between the insulator and a part of the casing for drawing the insulator downwardly.

2. In an electric appliance of the class described, a tubular casing; a socket insertible in the casing from the upper end of the latter; means interposed between the socket and the casing for relatively insulating these parts and for limiting the downward movement of the socket in the casing; an insulator supported by the socket and extending below the latter within the casing, a switching member mounted on the insulator and movable into and out of contact with a portion of the holder, the switching member having an actuating portion projecting laterally through the casing; a bottom plate engaging the bottom portion of the casing; and anchoring means interposed between the insulator and the bottom plate, for drawing the insulator and socket downwardly and for drawing the bottom plate upwardly against the bottom portion of the casing.

3. An electric appliance as per claim 2, in which the anchoring means comprise a member secured at its upper end to the insulator, and a screw extending upwardly through the bottom plate and threaded into the said member.

4. In an electric appliance of the class described, a tubular casing; a socket insertible in the casing from the upper end of the latter; means interposed between the socket and the casing for relatively insulating these parts and for limiting the downward movement of the socket in the casing; a bottom plate fitting the lower end of the casing, an anchoring structure interposed between the socket and the bottom plate for drawing the latter upwardly and for drawing the socket downwardly, a switching member carried by the anchoring structure and projecting

through the casing, and circuit connections respectively leading to the switching member and to a part of the socket.

5. An electric appliance as per claim 4, in which the casing includes a plurality of interfitting parts having relatively interengaging formations for limiting the extent of their interfitting, and in which the anchoring assembly operates also to clamp the said interengaging formations against one another so as to hold the casing parts in rigid assembly.

6. In an electric appliance of the class described, a tubular casing; a socket insertible in the casing from the upper end thereof, the socket including a metal socket shell and a terminal disposed within and insulated from the shell; means interposed between the socket shell and the casing for relatively insulating these parts and for limiting the downward insertion of the said shell in the casing; a metal member secured to the socket shell and extending downwardly from the latter; an anchoring member secured to a lower portion of the casing; an insulator interposed between the metal member and the anchoring member; a switching member mounted on the insulator and movable into and out of engagement with the said metal member; and circuit connections leading respectively to the switching member and of the said socket terminal.

7. In an electric appliance, of the class described, a current consuming device, a metallic holder for the said device, a tubular casing having an interior shoulder spaced from its upper end, an insulating washer seated on the shoulder and fitting the holder to support the holder and to insulate the holder from the casing; a conducting member secured to and extending downwardly from the holder, an insulator secured to and extending downwardly from the conducting member, a wire terminal mounted on the insulator, a second wire terminal disposed within the holder, means for insulating the second wire terminal from the holder and for continuously pressing the second wire terminal against the current consuming device, switching means interposed between the conducting member and the first named wire terminal, and means for anchoring the insulator to the casing.

8. An electric appliance of the class described, including a tubular casing having a lateral aperture and an assemblage insertible in the casing from one end thereof; the said assemblage including in rigid assembly a socket, means interposed between the socket and the casing for limiting the insertion of the said assemblage in the casing; and means for anchoring the assemblage in such limited inserted disposition; a switching member carried by the said assemblage, and a pair of conductors extending through the aperture

and connected respectively to the switching member and to a portion of the socket; the conductors being adapted to be secured to have their said connections made while drawn through the aperture and out through the said end of the casing, and before the said assemblage is inserted in the casing.

9. An electric appliance of the class described, including a tubular casing having a lateral aperture and an assemblage insertible in the casing from one end thereof; the said assemblage including in rigid assembly a socket, means interposed between the socket and the casing for limiting the insertion of the said assemblage in the casing; a pair of conductors extending through the aperture, one thereof being directly connected to a part of the socket, and a switching member connected to the other conductor and adapted electrically to connect the latter to another portion of the socket; the said assemblage including a rigid part secured to the casing

by the anchoring means and also including an insulator fastened to the said rigid part and supporting the switching member.

10. An electric appliance of the class described, including a casing composed of relatively superposed and interfitting portions having interengaging formations limit the extent of their interfitting; a socket disposed within the uppermost casing portion and insertible in the latter from the upper end thereof; means interposed between the socket and the uppermost casing portion for limiting the downward movement of the socket in that casing portion; and connections fast upon the socket and detachably secured to the lowermost casing portion for drawing the socket against the said interposed means and for holding the said formations on the casing portions in interengagement.

Signed at Chicago, Illinois, November 22nd, 1926.

JAMES J. GOUGH.
